CLAIM

The ornamental design for an LED lens, as shown and described.

DESCRIPTION

FIG. 1 is a perspective view of an LED lens showing our new design.

FIG. 2 is a front elevational view thereof, the rear elevational view being a mirror image of FIG. 2.

FIG. 3 is a left-side, elevational view thereof, the right-side, elevational view being a mirror image of FIG. 3.

FIG. 4 is a top plan view thereof.

FIG. 5 is a bottom plan view thereof; and,

FIG. 6 is a perspective view showing the LED lens of FIG. 1 being mounted on an LED subassembly, wherein the LED subassembly which consists of a rectangular substrate and an annular base is shown in broken lines for illustrative purposes only and forms no part of the claimed design.
